UNITED STATES PATENT OFFICE.

ALICE B. BOND, OF VISALIA, CALIFORNIA.

FIRELESS BROODER.

1,149,019.

Specification of Letters Patent.

Patented Aug. 3, 1915.

Application filed February 4, 1914. Serial No. 816,454.

To all whom it may concern:

Be it known that I, ALICE B. BOND, a citizen of the United States, residing at Visalia, in the county of Tulare and State of California, have invented new and useful Improvements in Fireless Brooders, of which the following is a specification.

This invention relates to improvements in brooders, the object of the invention being 10 to provide an improved device of this character which is extremely cheap and simple, which may be operated without heating means and which may be readily cleaned and kept in order.

15 One specific object of my invention is to effect improvements in the construction of the brooder whereby the chicks are prevented from crowding one another.

Another object is to effect improvements 20 in the construction of the brooding chamber whereby the animal heat arising from the chicks in the brooder is utilized for keeping the chicks warm.

Another object is to effect improvements 25 in the construction of the hovering blankets and in the means for holding them in place.

In the accompanying drawings:—Figure 1 is a vertical longitudinal sectional view of a brooder constructed in accordance with 30 my invention showing the peg top of the brooder in place. Fig. 2 is an elevation of a portion of the brooder. Fig. 3 is a plan view of the same, partly in horizontal section. Fig. 4 is a vertical transverse sectional 35 view of the same. Fig. 5 is a detail inverted perspective view of the peg top. Fig. 6 is a similar view of one of the hovering blankets.

The bottom 1 of the brooder may be made 40 of wood or other suitable material and is here shown as provided on its under side with transverse cleats 2 which serve to space it somewhat above the ground and prevent the bottom from becoming wet. Near one 45 end of the bottom, on its upper side are stops 3 and at opposite sides of the bottom are oppositely extending stops 4—5.

The body 6 of the brooder forms a brood- 50 ing chamber 8 and an exercising chamber 7 which are separated from each other by a vertical partition wall 9. The side walls 10 of the body of the brooder are narrowed vertically toward the outer end of the exer-

cising chamber so that they present inclined upper edges and the side walls are provided 55 on their inner sides, in the exercising chamber, with inclined supporting strips 11 on which may be placed a glazed sash 12 or a screen frame 13 at will, the glazed sash and the screen frame being detachably connected to the said walls so that either may be used according to the weather, the glazed sash keeping the exercising chamber warm and utilizing the sunlight for that purpose and the screen frame, when used serving to 60 thoroughly ventilate the exercising chamber. When the chicks are very young the glazed sash will ordinarily be used. When they get somewhat older the screen frame will be used within the discretion of the operator. The wall 9 is provided in its lower side at its center with a door opening 14 and with a hinged door 15 to open or close said opening. The outer end wall 16 of the exercising chamber has a similar opening 70 17 and hinged door 18 therefor.

The body of the brooder is detachably fitted on the bottom 1, one end and the sides of the brooder body being engaged by the stops with which the bottom is provided and 80 hereinbefore described. Hence the body of the brooder is prevented from being casually moved or slipped off of the bottom.

The front wall 19 of the brood chamber has an opening 20 at its lower side which extends entirely across the same. A bottom tray or drawer 21 is provided which is preferably made of sheet metal, such for instance as tin, or sheet iron, and is detachably fitted in the bottom of the brood chamber 90 and may be withdrawn therefrom through the opening 20, this bottom tray serving to catch the dirt and enabling it to be removed and the brood chamber to be readily kept in sanitary condition. At the outer side or 95 end of the bottom tray is a stop wall 22 which when the bottom tray is in place closes the opening 20.

In the side walls of the brooder chamber are glazed openings 23 to admit light and 100 to enable the chicks to be observed and the said side walls are each also provided with a series of spaced ventilating openings 24 to admit air, pivotally mounted shutters being provided to open and close said open- 105 ings at will, and draft baffles 26 being pro-

vided which are arranged on the inner sides of said side wall, at the inner ends of said openings and are open at their upper sides, and otherwise closed, the said baffles directing the currents of air which enter the brooder through the said openings upwardly and hence preventing drafts from moving transversely in the brood chamber over the chicks.

10 The front end wall and the wall 9 of the brood chamber are provided with horizontally arranged supporting strips 27 which are spaced a suitable distance from the bottom of the brood chamber and these strips 15 are provided on their upper sides with suitably spaced notches 28. Hover blankets 29 are provided each of which is formed at its upper side with a casing 30 through which extends a supporting rod 31. The ends of 20 the said rods project beyond the ends of the blankets and rest in the notches of the supporting strips 27. Hence the hover blankets are arranged in vertical position across the lower portion of the brood chamber and are 25 readily detachable therefrom. Each hover blanket is provided with spaced vertical slits which divide the same into short sections or flaps 32.

A top or board 33 is detachably fitted in 30 the brood chamber and is arranged to rest on the supports 27. In the corners of this top 33 are openings 34 and the said top is provided on its upper side with handle strips 35 to enable the same to be readily 35 placed in the brood chamber or removed therefrom. This top is provided with series of depending separating pegs 36 which are spaced equidistant apart both longitudinally and transversely of the top and are arranged 40 so as to extend down between the hover blankets when the said top is in place. These spaced pegs bound or form the corners of spaces each of which is of proper size to receive only one of the young chicks. 45 Hence the said pegs prevent more than one chick from getting in any one of the said spaces and therefore prevent the chicks from crowding one another. The peg top 35 when arranged in the brood chamber is spaced 50 both from the bottom and top of the brood chamber.

A cover 37 is provided for the brood chamber, which is detachably fitted thereon and is provided with side flanges 38 to hold 55 the cover in place thereon. When the peg top and the cover are in place a heating chamber 39 is formed in the brood chamber, above the peg top. The animal heat from the chicks rises into this chamber through 60 the openings in the peg top and is utilized for keeping the brood chamber at the required temperature without the employment of artificially produced heat.

When the brooder is used for older chicks 65 which do not require the use of hover blan-

kets said blankets will with their supporting rods and the peg top 33 be removed from the brood chamber and a top 40 will be employed in lieu of the peg top, this top 40 also, in connection with the cover forming a 70 heat retaining chamber in the upper portion of the brood chamber and being provided with openings 41 for the passage of the animal heat from the chicks and being also provided with handles 42 by means of which 75 the said top may be placed in the brood chamber or removed therefrom. The top 40 is here shown in Fig. 4 as having flanges 40^a on its upper side, at opposite ends, and said flanges being shown beveled on their 80 inner sides.

By the provision of the ventilating openings in the sides of the brood chamber, the shutters therefor, and the baffles at the inner sides of said openings the air admitted to 85 the brood chamber may be regulated as may be desired and hence the said brood chamber may be kept thoroughly ventilated without danger to the chicks. The cover also may be removed from the brood chamber 90 while the top 33 or the top 40 is in place if it be desired to allow animal heat from the chicks to escape.

Having thus described my invention, I 95 claim:—

1. In a brooder, a body forming a brood chamber, a top for said brood chamber and spaced pegs extending downwardly from said top into said brood chamber and so related as to bound or form the corners of 100 spaces, for the reception of one of the chicks.

2. In a brooder, a body forming a brood chamber, a top for said brood chamber, and spaced pegs extending downwardly from said top into said brood chamber, said pegs terminating short of the bottom of the brood chamber and being so related as to bound or form the corners of spaces, for the reception, each, of one of the chicks.

3. In a brooder, a body forming a brood chamber, said brood chamber having a cover and being also provided at a point spaced from the bottom and the cover with supporting elements on its sides, said supporting elements having spaced slots in their upper sides, supporting rods having their ends arranged in the spaced slots of said supporting elements, hover blankets attached to and depending from said spaced rods, a top detachably fitted in the brood chamber and bearing on said supporting elements and provided with openings establishing communication between the lower portion of the brood chamber and the air space in the upper portion thereof, and spaced pegs extending downwardly from said top into the brood chamber and removable therefrom with said top.

4. In a brooder, a body forming the brood chamber, supporting elements on the sides 130

of the brood chamber, a top for said brood chamber, detachably fitted on said supporting elements and spaced pegs carried by and extending downwardly from said top into 5 the brood chamber and removable from the body with said top.

In testimony whereof I affix my signature in presence of two witnesses.

ALICE B. BOND.
